Edgar D. Regar
Attorney

UNITED STATES PATENT OFFICE.

HAROLD D. REGAR, OF READING, PENNSYLVANIA.

CARBON-HOLDER.

1,362,140.

Specification of Letters Patent. Patented Dec. 14, 1920.

Application filed December 13, 1919. Serial No. 344,537.

To all whom it may concern:

Be it known that I, HAROLD D. REGAR, a citizen of the United States, residing at Reading, in the county of Berks and State of Pennsylvania, have invented certain new and useful Improvements in Carbon-Holders, of which the following is a specification.

This invention relates to improvements in carbon holders and it is intended for use in 10 arc lamps, moving picture machines, or any other instance where a like device or carbon member is to be secured.

The invention contemplates a carbon securing device in which the carbon is secured by means other than screws, which construction is generally conceded to be unsatisfactory, and to this end I have devised a construction whereby the carbon is held in position by means of an eccentric member 15 which bears against and securely holds the carbon in position.

It is known that heretofore eccentric devices for holding the carbon have been patented, but in the present invention I have 25 provided means, in the form of a weight, for not only securing the carbon, but for insuring a constant and uniform pressure against the carbon, which will substantially eliminate the danger of the "hold" thereon 30 becoming loosened or faulty.

The invention is more fully described in the following specification and clearly illustrated in the accompanying drawing, in which—

35 Figure 1 is a plan view of my device, and

Fig. 2 a longitudinal sectional view thereof, taken on the line 2—2 through Fig. 1.

The numeral 1 designates the body of the 40 holder, which is formed with a pair of parallel jaws 2 projecting from one side thereof, and 3 designates a bracket member at the opposite side, by means of which it may be secured to any suitable support. The numeral 4 designates a contact block, set into 45 the body member, between the jaws, and this block is formed with a vertical, V-shaped groove, against which the wall of the carbon, 5 is to be secured and held. The carbon, 50 bon 5 is held in vertical position between the jaws, as illustrated, and in contact with said block by means of a spindle 7 which spindle is formed with an eccentric 8 at the point where it is adapted to bear against 55 the wall of the carbon, that is, about midway of its length, so that, when the spindle

is turned, the eccentric portion of the spindle will not only contact with the carbon, but will securely hold it against the V-shaped groove of the block 4. 60

The spindle is provided with a lever 10, secured thereto preferably by a set screw 11, and adapted by its rise and fall, to partially rotate the spindle. This lever is provided with a weight 12, adjustably secured to its 65 free end, whereby the proper pressure may be secured as between the eccentric and the carbon.

The spindle is mounted in a pair of bearing blocks 14, which blocks are secured in 70 the ends of the jaws 2, and these blocks are laterally adjustable therein and are provided with set screws 15 for securing them at the desired points.

It is evident that with this construction, 75 I not only eliminate all screw holding features for the carbon, but that I secure a positive and constant hold on the carbon, through the eccentric contact member, actuated at all times by the weight of the 80 lever 10 and its adjustable member 12, for it will be noted that any tendency to loosen its grip on the carbon by the eccentric, will be immediately compensated for by the weight, which will insure that constant hold 85 that is so much desired.

The ease and simplicity with which the carbon may be released and replaced by another is evident and important, as it will be necessary only to raise the weighted lever 90 slightly, when the carbon will be released of all engagement and can readily be removed or re-adjusted.

Having thus fully described my invention, what I claim and desire to secure by Letters Patent is:—

1. In a carbon holder, the combination of a body member having a pair of parallel jaws and a contact block held in the body portion between the jaws, said block having a V-shaped vertical groove, with a shaft carrying an eccentric mounted in the ends of the jaws, a weighted lever secured to the shaft for imparting a slight rotary movement to the shaft, means for adjusting the shaft with relation to the contact block, and a carbon member adapted to be held between the said block and the shaft. 100

2. In a carbon holder, the combination of a body having a pair of parallel jaws, a removable contact block provided with a V-shaped vertical groove located in said body 105

between the jaw members, a rotatable shaft, bearing blocks adjustably arranged in the ends of the jaws and adapted to carry the shaft, an eccentric on said shaft, a carbon member adapted to be held between said block and the eccentric, and a weighted lever attached to said shaft whereby the eccentric is normally held against the said carbon.

3. In a carbon holder comprising a body portion having a pair of jaws and a contact block for the carbon, the combination there-

with of an adjustable rotary shaft mounted between the jaws, an eccentric on the shaft adapted to hold the carbon against the contact block, a lever secured to said shaft and 15 an adjustable weight on the lever whereby a predetermined and constant pressure may be exerted by the eccentric on the surface of the carbon.

In testimony whereof I affix my signature. 20

HAROLD D. REGAR.
